UNITED STATES PATENT OFFICE.

CHARLES L. CHISHOLM, OF MARYSVILLE, NEW BRUNSWICK, CANADA, ASSIGNEE TO
CHISHOLM TRANSMITTER & TELEPHONE INSTRUMENTS COMPANY.

TELEPHONE-RECEIVER.

1,046,554.

Specification of Letters Patent. Patented Dec. 10, 1912.

Application filed January 21, 1910. Serial No. 539,216.

To all whom it may concern:

Be it known that I, CHARLES L. CHISHOLM, a citizen of Canada, residing at Marysville, in the Province of New Brunswick, Dominion of Canada, have invented a new and useful Telephone-Receiver, of which the following is a specification.

This invention has reference to improvements in telephone receivers, though in part applicable to other acoustical instruments and its object is to provide means whereby a diaphragm may be caused to respond with greater accuracy than is the case with instruments of this character as ordinarily constructed.

In acoustical instruments employing sound receiving or transmitting diaphragms, such diaphragms are particularly susceptible to disturbing influences with consequent distortion of the sound waves with respect to the electrical undulations causing such sound waves through the intermediary of the diaphragm, or distortion of electrical undulations caused by the action of sound waves upon the diaphragm.

The ordinary diaphragm is circular and is supported at the periphery usually by means of two circular members in clamping relation, with the diaphragm edges between them. Even with the greatest care in manufacture a diaphragm so mounted has disturbing zones of unequal strain or stress which interfere materially with the operation of the diaphragm either for receiving or causing sound waves. Under commercial conditions the disturbing stresses and strains under which the diaphragms are placed become so marked as to interfere seriously with the propagation of overtones even to the obliteration of some of them and the timbre of the sound, especially in the transmission of vocal sounds is often sufficiently changed as to destroy the naturalness or recognizability of the voice.

By the present invention the ideal conditions for mounting of the diaphragm are closely approached and furthermore in the case of a telephone receiver these conditions are not disturbed since the invention comprises means for establishing magnetic conditions co-acting with the diaphragm to cause a faithful response of the diaphragm

to the electrical undulations entering the receiver so that the resultant waves caused by the diaphragm will not be wanting in the delicate sound waves upon which the naturalness or timbre of the sound depends.

The invention will be best understood from a consideration of the following detail description taken in connection with the accompanying drawings forming a part of this specification, in which drawings,

Figure 1 is a central longitudinal section of the hearing end of a telephone transmitter with the invention applied thereto, the showing being on a somewhat enlarged scale. Fig. 2 is a perspective view of the pole pieces of the structure of Fig. 1 on a larger scale. Fig. 3 is an end view of the structure of Fig. 2, slightly modified. Fig. 4 is a detail section of a portion of the diaphragm and the support therefor on an enlarged scale.

There is shown in Fig. 1 the ordinary casing 1 and cap 2 of an ordinary telephone receiver and these parts may be similar to the like parts of telephone receivers as commonly constructed. The cap 2 is provided with the usual cavity 3 for the reception of the ear of the user and this cavity terminates at the inner end in the usual sound passage 4.

There is shown a diaphragm 5 which may consist of a circular iron disk such as is usually employed in connection with telephone receivers and other like instruments wherein a diaphragm is set in vibration by electrical impulses to cause the sound waves corresponding to such impulses, or where the sound waves set the diaphragm into vibration to actuate members which in turn cause a record of the sound waves to be produced or cause electrical undulations by means of which the sound may be transmitted to and reproduced at a distance. In the case of the transmission or recording of the sounds the diaphragm 5 need not of course be of magnetic material. The diaphragm 5 is peripherally supported on a narrow ledge 6 formed in the inner wall of a ring 7. The ledge 6 is made as narrow as practicable so that a very much smaller area at the periphery of the diaphragm 5 is engaged by the ledge than is the case in

telephone receivers and like acoustical instruments as ordinarily constructed. The diaphragm is lodged in the ring 7 under practically no stress or strain and is there secured by a suitable cement indicated at 8.

When the parts are assembled the ring 7 with the diaphragm 5 cemented thereto under practically no stress or strain, is seated on the usual ledge at the hearing end 10 of the casing or hand hold 1 and then the cap 2 is applied and screwed down on the ring 7 in the same manner as this cap is usually screwed down upon the diaphragm, but the ring 7 is of sufficient width and 15 thickness to resist any action of the cap 2 to distort the ring from its original condition when the cap 2 is screwed against the ring in clamping relation thereto. The diaphragm 5 therefore remains in the original 20 condition under practically no stress or strain even when the ring 7 is clamped against the casing 1 by the cap 2 under conditions which would put a diaphragm directly clamped between these members under 25 such distortion as to materially affect its action.

By mounting the diaphragm in a peripheral ring of such stiffness as to resist the distorting effects of clamping the ring in place, 30 a close approach to or the full attainment of the ideal condition may be had without danger of disturbing these conditions whenever it is necessary to remove the clamp member and the diaphragm for inspection 35 or repairs, the diaphragm, when once set in the marginal ring maintaining its proper condition indefinitely and remaining unaffected by any stress or strain which might and does occur when the diaphragm is directly engaged by the clamping surfaces.

The ring 7 may if desired be made of some non-magnetic metal or of some other unyielding material, metal being usually preferred. For cementing the diaphragm to 45 the ring 7 shellac has been found suitable, and this shellac may be either pure shellac or a mixture thereof with rosin. However the invention is not at all limited to the particular kind of cement mentioned, but 50 this cement should be of a firm, unyielding character. Under some circumstances metallic cement may be used. With a diaphragm so mounted there is a succession of concentric zones from the center toward the 55 periphery which will vibrate in the order of the chromatic scale and these zones are without sensible distortion from stresses or strains due to the setting or clamping of the diaphragm.

With such a diaphragm as used in a telephone receiver experience has shown that the ordinary parallel pole pieces of the bi-polar receiver are not so well adapted to cause the actuation of the diaphragm as are 60 pole pieces corresponding approximately to

the shape of a zone of vibration of the diaphragm, especially when the zones are well marked as is the case with a diaphragm mounted as described herein. In accordance with the present invention there are 70 provided separate pole pieces 9 of the flat type commonly employed in bi-polar receivers, these pole pieces being surrounded by the usual coils 10, but at the outer or polar ends, the pole pieces are materially 75 modified as best shown in Fig. 2. Projecting from the adjacent sides or faces of the pole pieces immediately beyond the corresponding ends of the coils 10 are horns 11 at the outer corners of the pole pieces, these 80 horns projecting one toward the other but with their terminal ends spaced apart so that while the horns of one pole piece project toward the horns of the other pole piece they are separated by air gaps. The outer ends or polar extremities of the pole pieces are of segmental contour and in the same plane, the outer corners of the horns where they merge into the bodies of the pole pieces being cut away as indicated at 85 90 95 100 105 110 115 120 125 130. In the structure shown in Fig. 2 the plane segmental pieces of the polar extremities presented toward the diaphragm have the inner and outer edges concentric being all described about a common center and the continuity of these edges is broken only at the air gaps between the facing portions of the horns 11, the plane faces of the polar extremities being of equal width throughout and the curvature of the plane polar faces 100 is such that if these faces were continued across the air gaps they would form a complete ring of equal width throughout. When the parts are assembled the center of curvature of the polar faces presented to the diaphragm should coincide as nearly as practicable with the center of the diaphragm so that the pull of the magnets on the diaphragm will be in a zone of one pitch. The horns 11 are made to immediately overlie 110 the corresponding ends of the coils 10 so that the polar extensions are of the shortest practicable projection. The air gaps between the horns 11 are so proportioned to the distance between the plane polar faces of the pole 115 pieces and the adjacent face of the diaphragm that leakage across these air gaps is reduced to a minimum and consequently the full pull of the magnet pole pieces is exerted on the diaphragm and this pull is concentric with the center of the diaphragm in a zone of one pitch. Practical experience has shown that distortion or disturbance of the diaphragm is thus avoided and marked purity of tone results. Since there may be a tendency of magnetic leakage across the air gap with a consequent disturbance of the uniformity of the distribution of magnetism in the polar extremities, the ends of the horns of each pole piece where facing the 120 125 130

corresponding ends of the horns of the other pole piece may be reduced as indicated in Fig. 3, or may be otherwise modified so that the magnetic leakage is correspondingly 5 reduced.

What is claimed is:—

1. In an acoustical instrument, a diaphragm having a stiff, unyielding peripheral setting individual to the diaphragm and 10 to which the latter is firmly secured without stress or strain, the seat for the diaphragm in its setting being of inconsiderable radial extent.
2. In an acoustical instrument, a diaphragm, and a ring individual to the diaphragm and resistant to distorting forces and to which the diaphragm is firmly secured without stress or strain.
3. In an acoustical instrument, a diaphragm, and a stiff unyielding ring united 20 to the periphery of the diaphragm without stress or strain, the diaphragm and its peripheral ring being bodily attachable to and movable from the acoustical instrument in which it is used.
4. A telephone receiver having a diaphragm with a peripheral setting resistant to distorting forces individual thereto and provided with a seat of inconsiderable radial 25 extent for the diaphragm, and means for holding the diaphragm to its seat without stress or strain.
5. A telephone receiver having an electromagnet provided with straight pole 30 pieces each terminating in a polar face in line with the body portion of the pole piece and provided with laterally curved portions at the polar ends, the curved portions of one pole piece being directed toward those of 35 the other and concentric with the longitudinal central axis of the magnet, those extremities of the straight portions and of the curved portions together constituting

the polar faces of the pole pieces being all 45 in one plane.

6. In an acoustical instrument, a diaphragm free from stress and strain and provided with a peripheral portion individual thereto and resistant to forces tending to impart stress or strain to the diaphragm 50 incident to clamping said peripheral portion in an acoustical instrument.

7. In an acoustical instrument, a diaphragm and a ring individual to the diaphragm and resistant to distorting forces 55 and to which the diaphragm is firmly cemented substantially without stress or strain.

8. In an acoustical instrument, a ring of stiff, unyielding material having a seat of 60 inconsiderable radial extent in its inner edge, and a diaphragm firmly cemented to said seat substantially without stress or strain.

9. In an acoustical instrument, a dia- 65 phragm having a stiff unyielding peripheral setting individual to the diaphragm and provided with a seat for the diaphragm of inconsiderable radial extent, and a firm cement uniting the diaphragm peripherally 70 to the setting substantially without stress or strain.

10. A telephone receiver having a dia- 75 phragm with a peripheral setting individual thereto and provided with a seat of inconsiderable radial extent for the diaphragm, and a cement for holding the diaphragm to its seat whereby the diaphragm is substantially free from stress or strain.

In testimony that I claim the foregoing 80 as my own, I have hereto affixed my signature in the presence of two witnesses.

CHARLES L. CHISHOLM.
